UNITED STATES PATENT OFFICE.

MARY LOUISE HILLYER, OF GOLIAD, TEXAS.

BED.

1,095,397.

Specification of Letters Patent.

Patented May 5, 1914.

Application filed September 15, 1913. Serial No. 789,869.

To all whom it may concern:

Be it known that I, MARY LOUISE HILLYER, a citizen of the United States, residing at Goliad, in the county of Goliad and State of Texas, have invented certain new and useful Improvements in Beds, of which the following is a specification, reference being had therein to the accompanying drawing.

This invention relates to a bed attachment and the principal object of the invention is to provide a device which will serve as a back rest for an invalid.

Another object of the invention is to so construct the back rest that it may be conveniently connected with the bed so that it may be angularly disposed.

Another object of the invention is to so mount the back rest that it will be out of the way when not in use, but which does not need to be removed from the bed when it is desired to use the same.

With these and other objects in view, this invention consists of certain novel combinations, constructions and arrangements of parts as will be hereinafter fully described and claimed.

This invention is illustrated in the accompanying drawing, wherein:—

Figure 1 is a perspective view of the bed with the back rest in a position which it assumes when not in use. Fig. 2 is a perspective view of the bed with the back rest in a position for use. Fig. 3 is a section taken along the line 3—3 of Fig. 1 with the head posts of the bed broken away to show the manner in which the pivot rod of the back rest is mounted. Fig. 4 is a perspective view of a back rest in a position for use, the dotted line position indicating a folded position of the back rest. Fig. 5 is a section taken along the line 5—5 in Fig. 3. Fig. 6 is a section taken along the line 6—6 in Fig. 1.

This invention is intended as an attachment for a bed which is provided with the head board 10 and foot board 11 which are connected by side rails 12. These side rails 12 form supports for the slats 13 by which the springs and mattress 14 are supported. Guard rails 15 are carried by the bed each of which has a leg 16 entering a sleeve 17 so that the guard rails 15 can be vertically disposed and held in an adjusted position by the set-screws 18. These guard rails are intended to prevent any danger of a person who is restless from rolling out of bed, and are also intended to form a support for the

table 19 which is pivotally connected with one of the guard rails 15 by the hinge plates 20. This table can hang from the rail 15 against one side of the bed or may be turned to the position shown in Fig. 2 and held in this position by the set-screws 21 which are carried by the hinge plates 18.

The head board 10 has its side posts 22 provided with aligned openings 23 so that a pivot rod 24 can be passed through these openings to pivotally mount a back rest which is carried by the head board. The back rest is provided with a frame made up of the side arms 25 and a connecting rod 26 pivotally mounted upon the rod 24 constituting the attaching bracket for the back rest. A catch 27 is carried by one of the side arms 25 and is intended to engage a pin 28 carried by one of the side posts 22 so that bracket can be held in an adjusted position as shown in Figs. 2 and 4.

The supporting board of the back rest is provided with side bars 29 which are connected by the upper and lower rods 30 and 31 and which are provided with longitudinally extending slots 32 through which the rod 26 passes so that the supporting board will be slidably connected with the attaching frame. The lower ends of the side bars 30 are provided with notches 33 which are intended to engage the rod 24 so that when the back rest is in the folded position shown in Fig. 1, there will be no danger of the supporting board slipping out of the proper position. These notches also form points which to a certain extent dig into the mattress and thus afford means for preventing the board from slipping out of the angular position in which it is placed when used.

The operation of this device will be readily understood from a comparison of Figs. 1, 2 and 4. When the device is not in use, the back rest is raised to the position shown in Fig. 1 with the catch 27 engaging the pin 28 as shown in Fig. 5, thus holding the bracket frame in the vertical position. The back supporting board is also raised to the vertical position with the rod 24 fitting into the notches 33. This will hold the back rest securely in a folded position and prevent any danger of its accidentally slipping loose. When it is desired to use the back rest, the catch 27 is released and the bracket swung forwardly as far as desired and the catch is again brought into engagement with the pin 28, and will thus hold the back rest in this

position. The back supporting board can then be swung to any angle desired as shown in Figs. 2 and 4 and the device is then in a position for use. If it is desired to serve a meal, the table 19 can be swung from the side of the bed 2 to the position shown in Fig. 2 and held in this position by tightening the set-screws 21.

What I claim, is:

10. A bed attachment comprising a supporting head, a rod extending across the lower portion of said head, arms pivotally secured to said rod, a secondary rod secured to the upper ends of said arms, a back rest pivotally and slidably secured to said secondary rod for allowing the back rest to be easily adjusted, said back rest comprising side

bars, the lower ends of said bars being rounded and provided with U-shaped notches, said back-rest adapted to be carried by said first-mentioned rod so as to allow said rod to fit within said notches for holding said rest in a vertical position independent of secondary securing means, the lower portion of said bars adapted to sink into the bed-clothing when in use to hold the rest in a set position.

In testimony whereof I hereunto affix my signature in presence of two witnesses.

MARY LOUISE HILLYER.
